[57] CLAIM

We claim the ornamental design for a computer mouse, as shown and described.

DESCRIPTION

FIG. 1 is a right side elevational view of a computer mouse showing our new design;

FIG. 2 is a top plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The bottom of the computer mouse forms no part of the claimed design.
